(57) **CLAIM**

The ornamental design for a toy bubble gun, as shown and described.

DESCRIPTION

FIG. 1 is a top, front and right side perspective view of a toy bubble gun, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view of the toy bubble gun shown in FIG. 1;

FIG. 10 is an exploded perspective view of the toy bubble gun shown in FIG. 2; and,

FIG. 11 is an enlarged view of portion 11 shown in FIG. 9. The broken lines in the drawings depict portions of the toy bubble gun that form no part of the claimed design.

1 Claim, 11 Drawing Sheets
